(57) **CLAIM**

The ornamental design for a robotic system enclosure, as shown and described.

DESCRIPTION

FIG. 1 is a top perspective view of a robotic system enclosure, showing our new design;

FIG. 2 is a front elevational view of the robotic system enclosure of FIG. 1;

FIG. 3 is a back elevational view of the robotic system enclosure of FIG. 1;

FIG. 4 is a left elevational view of the robotic system enclosure of FIG. 1;

FIG. 5 is a right elevational view of the robotic system enclosure of FIG. 1;

FIG. 6 is a top plan view of the robotic system enclosure of FIG. 1;

FIG. 7 is a bottom plan view of the robotic system enclosure of FIG. 1;

FIG. 8 depicts a top perspective view of another embodiment of a robotic system enclosure, showing our new design;

FIG. 9 is a front elevational view of the robotic system enclosure of FIG. 8;

FIG. 10 is a back elevational view of the robotic system enclosure of FIG. 8;

FIG. 11 is a left elevational view of the robotic system enclosure of FIG. 8;

FIG. 12 is a right elevational view of the robotic system enclosure of FIG. 8;

FIG. 13 is a top plan view of the robotic system enclosure of FIG. 8; and,

FIG. 14 is a bottom plan view of the robotic system enclosure of FIG. 8.
